JOSEPH FRIEDLANDER, OF NEW YORK, N. Y.

EYEGLASSES.

No. 923,506.

Specification of Letters Patent.

Patented June 1, 1909.

Application filed February 13, 1909. Serial No. 477,545.

REISSUED

To all whom it may concern:

Be it known that I, JOSEPH FRIEDLANDER, a citizen of the United States, and a resident of the city of New York, borough of Manhattan, in the county and State of New York, have invented new and Improved Eyeglasses, of which the following is a full, clear, and exact description.

This invention relates to eyeglasses, and especially to the means for mounting the clips which hold the eyeglasses in position on the nose.

More particularly the invention is concerned with that type of eyeglasses which comprise levers attached to a fixed bow or bar. These levers are attached to posts formed at the ends of the bow and near the inner edges of the lenses. Adjacent to the posts, the clips are pivotally attached to the levers. As usually constructed, the pivotal connection between the clip and the lever is in plain view from the front. This tends to give this type of eyeglass a cumbersome construction which is in itself objectionable, and seriously detracts from the selling qualities of such eyeglasses.

The object of this invention is to provide an eyeglass of this general type, having an improved construction in which the point of connection between the clip and the lever is substantially concealed behind the post.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a front elevation of a pair of eyeglasses constructed according to my invention, the outer portions of the lenses being broken away; Fig. 2 is a plan showing one of the levers and clips, together with a short portion of the bridge and a portion of the adjacent lens; Fig. 3 is a perspective showing one side of the eyeglasses with the lens removed, and further illustrating details of the construction; and Fig. 4 is a detail view upon an enlarged scale and is a vertical section taken on the line 4—4 of Fig. 3 and passing through the post.

Referring more particularly to the parts, 1 represents the bow or bar of the eyeglasses, the ends of which are enlarged so as to form posts 2. These posts are provided with an-

nular pockets 3, respectively, as indicated in Fig. 4, which pockets receive coil springs 4. On the upper side of each post, a lever 5 is seated, held in position by a screw 6 which passes down centrally through the post, as indicated. The spring 4 is a simple coil spring, the lower end of which is held in the lower portion of the post in a recess 7. The upper end of the spring is attached to the lever 5, and the spring exerts its force in such a way that it tends to move the handle 8 of each lever away from the vertical central axis between the lenses. As indicated, these handles 8 project toward the front and diverge slightly. Beyond each post a lens clamp 10 is provided of any suitable construction.

Referring especially to Fig. 4, it will be seen that the lever 5 passes across the post in a substantially horizontal position. Just beyond the post, that is, just in the rear thereof, the lever, which is formed of thin flat sheet metal, is bent downwardly so as to form an inner leaf 11, and at the lower end of this leaf 11, the material is bent upwardly to form an outer leaf 12. Between the leaves 11 and 12, an open throat 13 is formed. In this way a substantially U-shaped socket is formed, in which the clip 14 is attached. In order that this socket shall be concealed behind the post as suggested, it is necessary to make it of very small dimensions. The clip 14 is of substantially the form shown, having a vertically elongated body 15 with a laterally projecting ear 16 which is disposed in a plane substantially at right angles to the body of the clip. This ear 16 projects into the throat 13, as indicated most clearly in Figs. 3 and 4. In the U-shaped socket which receives the ear 16 in this manner, there is provided a pivot screw 17, the head of which is countersunk into the outer leaf 12, as indicated in Fig. 4. The inner portion of the screw is provided with threads and these engage in similar threads which are formed in a threaded opening 18 formed in the inner leaf. As it is necessary, as stated, for these parts to be very small in order to be concealed behind the post, the pivot screw is of extremely small diameter. In order to accomplish my object it is therefore necessary to increase the length of the threaded engagement between the screw and the inner leaf. To do this, I form on the inner face of the leaf 11, an enlargement or hub 19. In this way the holding power of the

screw is increased so that I can employ a screw of a smaller diameter than would otherwise be possible. The axis of this screw is in a substantially horizontal plane.

5 With eyeglasses constructed as described, evidently the clips will readily adjust themselves to the sides of the nose and will retain themselves in position by the pressure of the springs 4.

10 Having thus described my invention, I claim as new and desire to secure by Letters Patent, —

15 1. An eyeglass having posts at each side thereof, levers pivotally attached to said posts and passing across said posts in a substantially horizontal position, the inner extremities of said levers having downward extensions forming inner leaves lying adjacent to the posts and upward extensions beyond said inner leaves lying remote from said posts, clips having ears projecting into the spaces between said inner leaves and said outer leaves, and pivot screws passing through said outer leaves and said ears and 25 having a threaded engagement with said inner leaves, said leaves being disposed directly behind said posts and concealed thereby.

2. Eyeglasses having a bar with posts 30 formed near the extremities thereof and adjacent to the point of attachment of the lenses, levers passing across the upper sides of said posts and pivotally attached to said

posts, springs constraining said levers, said levers being bent to form U-shaped sockets 35 at the inner ends thereof concealed behind said posts, said U-shaped sockets comprising respectively, an inner leaf extending downwardly and an outer leaf extending upwardly, clips having ears projecting into said sockets respectively, and pivot screws passing through said sockets, having their heads seating on said inner leaves and having threaded extensions making threaded engagement with said inner leaves, said inner leaves having hubs projecting toward said posts.

3. An eyeglass having posts at each side thereof, levers pivotally attached to said posts, the inner extremities of said levers having laterally bent extensions disposed behind said posts and concealed thereby, clips having ears, and pivot screws attaching said ears to said lateral extensions and having threads engaging the same, said lateral 55 extensions having hubs formed thereupon projecting toward said posts and receiving the body of said pivot screw.

In testimony whereof I have signed my name to this specification in the presence of 60 two subscribing witnesses.

JOSEPH FRIEDLANDER.
